(57) **CLAIM**

We claim the ornamental design for a personal flotation device back panel, as shown and described.

DESCRIPTION

FIG. 1 is a perspective view of a personal flotation device back panel showing my new design;

FIG. 2 is a top view thereof;

FIG. 3 is a front elevational view thereof;

FIG. 4 is a right side elevational view of the personal flotation device back panel, the left side elevational view is a mirror image thereto; and,

FIG. 5 is a front elevational view of a personal flotation device back panel illustrating a second embodiment of my design.

The ornamental design which is claimed is shown in solid lines in the drawings. The broken lines in the drawings are for illustrative purposes only and form no part of the claimed design.
